INVENTOR

Harriette E. Hodgson
BY

J. Hanley
ATTORNEY

UNITED STATES PATENT OFFICE.

HARRIETTE ENSLEY HODGSON, OF NEW YORK, N. Y.

CAR.

Application filed December 15, 1924. Serial No. 755,871.

To all whom it may concern:

Be it known that I, HARRIETTE ENSLEY HODGSON, a citizen of the United States, and a resident of New York city, in the county 5 and State of New York, have invented a certain new and useful Improvement in Cars, of which the following is a specification.

The conditions of rail travel in large 10 cities like New York have long been very bad, owing to the great congestion; and it is doubtful whether construction of new lines can do much more than keep pace with increase of population. A large part of 15 those who travel by subway or elevated during rush hours are obliged to stand, and even at other times it is often impossible for passengers to find seats. In a somewhat 20 different degree the same conditions are true of surface lines. The situation urgently demands a remedy, and I have sought to provide a simple and practical one, applicable to either old or new cars, and requiring no radical changes. Numerous arrangements in cars of ordinary seats have been 25 tried, but in no case has the seating capacity been adequate. In contradistinction to such plans, my invention is based upon the thought that real advantage can be secured 30 by partly seating a large number of persons, instead of fully seating only a few while the rest stand. With seating provisions such as are herein illustrated, the seating capacity of a car can be more than 35 doubled, the posture is sufficiently restful, and the average condition of a car full of people is very greatly improved.

To carry out the invention I have devised what I shall term, for convenience, perch 40 seats. In the best embodiment, the car is provided with a narrow longitudinal aisle running substantially the full length of the car, and these perch seats are placed transversely in two rows at opposite sides of the 45 aisle. The seats have vertical frames rising considerably higher than the backs of ordinary car seats, and the frames are placed one behind the other quite close together, forming narrow stalls open to the 50 aisle. The seats proper on these frames are much narrower than regular seats, being, for example, about six inches wide from front to back, and are placed high on the frames, approximately half again as high 55 as ordinary seats, the design being such that the passengers perch on the ledge-like seats,

lightly bracing themselves with their feet against footrails on the frames in front or against the floor. The seats proper are slightly inclined forward and downward, 60 and they are reversibly connected to the frames so that they can be shifted from one side to the other, according to the direction of travel. Short brackets with inclined tops on the frame sustain the seats in either 65 position, and these brackets may be either fixed, in which event there are two seats on opposite sides of the frames, or they may be movable from one side of the frames to the other. 70

In the accompanying drawings illustrating the invention:

Fig. 1 is a floor plan of a car embodying the invention;

Fig. 2 is a vertical longitudinal sectional 75 elevation;

Fig. 3 is a vertical transverse section on a larger scale;

Fig. 4 is a vertical section on the line 4—4 of Fig. 3; and 80

Fig. 5 is a detail horizontal section illustrating a reversible and foldable bracket.

The floor of the car is marked 1, the sides 2, and the ends 3. There are center and end doors on each side, marked, respectively, 4 and 5, with central and end door spaces 6 and 7. The longitudinal aisle running from one end door space 7 to the other and intersecting the center door space 7, is marked 8. 90

The seats 9 are arranged transversely in rows on opposite sides of the aisle. With an aisle about sixteen inches wide, there can be a row of seats on one side to accommodate three persons each, and a row on the 95 other side to accommodate two passengers each. The total seating capacity, as shown, is one hundred and ten. It will be understood, however, that all figures and proportions are merely illustrative. Greater width 100 of aisle, and more seating room for the individual passenger, would result if seats were designed to hold only two passengers on both sides of the aisle, and such a modification is to be regarded as within the invention. 105

The seats have vertical, transverse, supporting and back frames 10, which are firmly anchored in the floor. The frames in each row are placed comparatively close 110 together, as the passengers do not assume a full sitting position. As a matter of illus-

tration, a spacing of sixteen inches, or somewhat more, may be understood.

The ledge-like seats proper are marked 11. The width of these seats, from front to rear, may be about six inches, but again I do not wish to limit myself to precise measurements. They are designed to be wide enough to afford a sufficient rest to a person in a half-sitting, half-standing position, with 10 his feet upon the floor or upon the foot rail 12 of the frame in front. The seats incline at a slight angle, as shown. Their height from the floor is necessarily considerably greater than that of ordinary car seats. I 15 contemplate a height of about thirty inches, but this is, of course, subject to variation.

The seats are pivoted or otherwise movably connected to the frames, so that they can be reversed to extend either forwardly 20 or rearwardly, as illustrated in Fig. 4, the frames having open spaces which permit of this movement. Pivoting of the seats also permits them to be turned up to a substantially vertical position, when passengers enter or leave the stalls. Friction will prevent the seats being turned all the way over at times, or if thought desirable suitable means may be provided for that purpose.

The seats are supported upon small 30 brackets 12 on the frames, the tops of these brackets being inclined. There may be fixed pairs of these brackets on opposite sides of the frames. Fig. 5 indicates a movable form of bracket 12^a, which is hinged to the 35 support so that it can be turned from one side to the other, and can also be disposed in the plane of the frame if not in use. Again, friction or more positive means may be relied upon to keep such brackets in the 40 positions desired.

The upper parts of the frames 10 carry back-rests. These may be in the nature of flat boards or panels as shown at 13 at the 45 left of Fig. 3, or may be composed of bars 13^a close together, as illustrated at the right of the same view, though I prefer the former.

The frames are preferably made in an

inexpensive way of piping, and at the sides next the walls of the car they may be tied 50 together by longitudinal members 14 and 15.

The door spaces 6 and 7 are preferably, though not necessarily, used for seating, to the extent of four of the perch seats as illustrated. The frames adjacent the doors 55 may therefore be provided with short wings 16 to afford lateral support for the shoulders of passengers occupying these seats, to obviate any danger of accident when the doors are open.

A preferred and simple embodiment of the invention has been described, but it will be understood that the invention is not limited to the precise form and arrangement shown and described, and that there 60 may be numerous changes in the general plan without departing from essentials.

What I claim as new is:

1. A passenger car in which large seating capacity is obtained by perch seats, comprising vertical frames placed close one behind another and narrow, ledge-like seats on the frames at a height materially higher than ordinary car seats, the said seats being reversibly mounted on the frames so that 75 they can be shifted from one side to the other of the frames.

2. The herein described perch seat for railroad cars comprising a vertical frame, a narrow, ledge-like seat on the frame at a 80 height materially higher than ordinary car seats, said seat being reversibly mounted on the frame so that it can be shifted from one side to the other, and short brackets on the frame to support the seat in either positon. 85

3. The herein described perch seat for railroad cars comprising a vertical frame, a narrow, ledge-like seat on the frame at a height materially higher than ordinary car seats, said seat being reversibly mounted on the frame so that it can be shifted from one side to the other, and short brackets on the frame to support the seat in either position at an inclination. 90

HARRIETTE ENSLEY HODGSON.
